UNITED STATES PATENT OFFICE

110,403

DESIGN FOR A PARK TRAIN BODY

William B. Schmidt, Chicago, Ill.

Application March 10, 1938, Serial No. 75,737

Term of patent 14 years

To all whom it may concern:

Be it known that I, William B. Schmidt, a citizen of the United States, residing at Chicago, in the county of Cook and State of Illinois, have invented a new, original, and ornamental Design for a Park Train Body, of which the following is a specification, reference being had to the accompanying drawing, forming a part thereof.

In the drawing:

Figure 1 is a perspective view as seen from the side and front portions showing the park train body of my new design;

Figure 2 is a perspective view showing the back end of the rear top and the door sides of the intermediate and forward body;

Figure 3 is a side elevational view thereof taken from the window side of the body; and

Figure 4 is a front elevational view of the body.

I claim:

The ornamental design for a park train body, as shown.

WM. B. SCHMIDT.
